UNITED STATES PATENT OFFICE.

GEORGE B. PICKOP, OF NEW HAVEN, CONNECTICUT, ASSIGNOR TO THE MALLEABLE IRON FITTINGS COMPANY, OF BRANFORD, CONNECTICUT, A CORPORATION OF CONNECTICUT.

CORE-MAKER'S TABLE OR THE LIKE.

Application filed August 27, 1919. Serial No. 320,189.

To all whom it may concern:

Be it known that I, GEORGE B. PICKOP, a citizen of the United States, residing in the city and county of New Haven, State 5 of Connecticut, have invented certain new and useful Improvements in Core-Makers Tables or the like, of which the following is a full, clear, and exact description.

This invention relates particularly to 10 coremakers' tables or benches such as used in the manufacture of sand cores for small castings, for example, pipe fittings, although the device of my invention is applicable to other purposes.

15 In making small sand cores, it is customary to produce them by completely filling with packed sand so-called core boxes, consisting of mating upper and lower sections, usually of cast metal, corresponding internally in shape to the core which is to be formed. It is customary to fill the core boxes on tables capable of accommodating a quantity of the properly conditioned sand. 20 The lower section of the core box being placed on the table top, such section is 25 heaped up with sand which is properly packed in the same, the top section of the box is then placed on the lower section for obtaining the desired upper contour of the core, the top section is then lifted off, and 30 the core removed from the table, for drying, while still occupying the lower part of the box.

35 Before parting the box sections it has been customary heretofore to rap or hammer the box with a wooden mallet or like implement in order to obtain a clean removal of the top section without any sand adhering to the same and consequently without creating 40 holes or flaws in the upper surface of the core caused by particles of the moist sand adhering to the upper box section when the latter is lifted off. The rapping of the core boxes by hand in this manner consumes 45 a considerable part of the time and attention of the operator and is, therefore, objectionable from a production standpoint; and, furthermore, by the direct application of blows to the core boxes the latter are 50 likely to be injured and to have a short life.

One of the objects of the present invention is to provide a coremaker's table with a simple and efficient device for rapping or vibrating the boxes preparatory to the part-

ing of the sections thereof, which rapping 55 device is operated by power, preferably compressed air, and overcomes the objections above noted.

Another object is to provide a table with 60 means readily controlled by the molder or operator for vibrating work resting upon the top of the table.

Another object which I have in view is 65 the provision of a table suitable for the above and other purposes, having within the confines of its top a part or section which can be readily set in vibration when it is desired to bring that about.

Still another object is to furnish a table 70 for coremaking and like purposes having a floating platen with effective means for rapping or vibrating the same, such platen and the actuating means therefor being of improved construction and arrangement.

To these and other ends the invention 75 consists in the novel features and combinations of parts to be hereinafter described and claimed.

In the accompanying drawings:

Fig. 1 is a top plan view of a table embodying my improvements showing the floating vibratory platen, the surrounding portion of the table being broken away;

Fig. 1^A is a diagrammatic top plan view 80 on a small scale of the complete table;

Fig. 1^B is a front elevation on a small scale of the complete table, this view being also somewhat diagrammatic in character;

Fig. 2 is a side elevation of that part of 90 the table shown in Fig. 1 on the same scale as Fig. 1;

Fig. 3 is an end view of the table parts shown in Fig. 1;

Fig. 4 is a section on line 4—4 of Fig. 1; 95 and

Fig. 5 is a section on line 5—5 of Fig. 1.

In the embodiment of my invention selected for illustration, I have shown a table 10^a (Figs. 1^A and 1^B), which in its general nature is similar to the ordinary coremaker's 100 table, having a top 10 on which sand may be piled and on which the core box may be filled. The table top is supported by suitable legs 10^b. In the table top is a suitable opening for a vibratory table section, or platen 12 and its surrounding supporting frame 11. In this case a rectangular opening is formed in the top of the table to 105

receive the rectangular metal frame 11. The platen and its frame are located within the margins of the table top in a convenient position for the workman standing in front 5 of the table, who fills the core box while the latter is on the platen. The frame 11 may be made of metal and, as shown, it has a horizontally extending portion 13 and a vertically extending wall portion 14. The 10 horizontally extending portion 13 rests upon the upper face of the table top around the opening and may be secured in position by screws 15. While the frame extends slightly above the upper surface of the table, 15 the former and the platen are approximately flush with such surface, the outer edge of the frame being beveled, as shown at 16. The vertical walls 14 of the frame form a boxlike structure in which the platen or 20 section 12 is movably mounted and in the example illustrated the platen is mounted for vertical sliding movement. At the lower ends of the vertical walls 14 horizontal flanges 17 project inwardly for supporting 25 the platen. The latter which has reinforcing ribs 18 on its under surface fits fairly snugly within the supporting frame and the marginal side and end portions of the platen are provided with downwardly extending 30 ribs 18' which are positioned slidably to engage the inner surface of the frame.

The platen is supported in the frame by bolts 19, the upper ends of which are screwed into threaded sockets in the corners of the platen. These bolts are vertically disposed and pass through perforations in the flanges 17. About each of the bolts is coiled a spring 20 interposed between the corresponding flange 17 and the under surface of the platen. Nuts 21, 22 are threaded upon the lower ends of the bolts to provide for vertical adjustment of the platen, which preferably lies normally substantially flush 45 with the upper surface of its inclosing frame. After the nuts 21 have been properly adjusted, they are locked in adjusted position by the lock nuts 22.

The lower face of the platen is provided 50 approximately at its center with a downwardly projecting lug 23 and to this lug is rigidly secured a pneumatic vibrator 24. The upper end of the vibrator casing is rigidly secured to the lug 23 by a bolt 25 and nut 26. The vibrator 24 may be supplied with compressed air by a flexible hose or tube 27, which leads to a controlling valve 28 located beneath the platen and from the valve 28 the air is conducted to the vibrator 55 by a second flexible hose or tube 29. The air valve 28, which is shown as of the sliding plunger type, is mounted upon one of the downwardly extending end walls 14 of the frame 11, for which purpose a bracket 60 65 30 is attached to said wall by lugs 31 and

bolts 32. The bracket 30 is provided with a downwardly projecting post 33 through the lower portion of which is a transverse hole in which one of the nipples 28' of the air valve 28 is mounted. A set screw 34 70 clamps the nipple in this hole so as to rigidly secure the valve to the bracket. The air valve is controlled by a bell crank lever 35 pivoted on supporting bracket 30 by trunnions 36 on the lever, which trunnions engage hooks 37 on the bracket 30. The downwardly extending portion 38 of the bell crank lever is arranged to abut the outer end of the sliding plunger 39 of the air valve while the upper end of lever 35 is 80 adapted to engage the under surface of the platen in such a manner that the air valve may be controlled by depression of the platen. In order that the parts just described may be adjusted so that the valve 28 will be opened to operate the vibrator 24 when the platen 12 is depressed to a predetermined degree in opposition to the springs 20, the upper end of lever 35 makes engagement with the under surface of the platen by means of an adjustable bolt 40 carried by the lever, which bolt is threaded in a socket in the lever terminal so that the upper end of the bolt may be engaged by the under surface of the platen. When adjusted the bolt 40 may be locked in position by a lock nut 41.

The operation of the device will be more or less obvious from the foregoing description. In making a core the lower section of a core box is placed on the platen 12 and filled with sand which is available on the fixed portion of the table top. The upper section of the box is then placed on the lower section in the usual manner. Before lifting off the upper box section, the floating platen 12 is set into vibration by opening the air valve 28. With the particular machine illustrated, the air valve may be opened very readily merely by subjecting the platen to a predetermined downward pressure which may be very conveniently done by the hands of the operator. All that it is necessary for the operator to do is to press downwardly on the platen with a little more force than that previously exerted in filling the core box. When the platen is forced downwardly, the L-shaped lever 35 will open the air valve and start the platen to vibrating in an obvious manner, the vibration being continued until the pressure on the platen is removed. In this manner the sections of the core box may be parted without forming holes or flaws in the core due to sand adhering to the box sections. The controlling pressure may be readily applied to the platen without the operator being required to move his body, and in fact without requiring anything but the slightest manual movement of the operator whose hands are 110 115 120 125 130

naturally in a position to control the vibration with a minimum of wasted motion.

The coiled springs 20, should, of course, be sufficiently strong to sustain the platen in its upper position, flush with the table top, when it holds the load of the core box or other work upon the same, and such springs should also have a certain amount of additional supporting power so as to prevent the depression of the platen by the operator when he packs the sand in the core box. By providing for the adjustment of the springs 20 and for the regulation of the engagement between the lever 35 and the under surface 15 of the platen, the device may obviously be adjusted to suit the conditions of different work and the requirements of different operators.

While I consider it preferable to mount the platen, constituting a section of the table top adapted to be set in vibration independently of the main portion of such top, in the manner herein particularly described, adapting it for rectilinear movement in its frame in a vertical direction, various changes in this and other respects may be made without departing from the broad principles of the invention as defined in the claims. It is obvious, for example, that means other than those particularly described for cushioning the table and mounting it for floating movement, so that objectionable vibration is not imparted to the main part of the table top, will suggest themselves to those skilled in the art.

What I claim is:

1. A vibrating table having a platen, means for yieldingly supporting the platen, a normally inoperative vibrator adapted to vibrate said platen, and means for setting the vibrator in operation automatically by a predetermined amount of downward pressure exerted on the platen.

2. A vibrating table provided with a vertically movable platen, means for yieldingly supporting said platen, a normally inoperative vibrator adapted to vibrate said platen, and means controlled by said platen for setting the vibrator in operation.

3. A vibrating table provided with a vertically movable platen, means for yieldingly supporting said platen, a normally inoperative vibrator adapted to vibrate said platen, and means controlled by the pressure exerted in a downward direction upon said platen for setting the vibrator in operation.

4. A coremaker's bench or table having a top comprising a fixed portion for holding the working materials and a vibratory portion cushioned against downward movement on which the core is formed.

5. A device of the character described comprising a table, a platen movably mounted in the top of the table, a normally inoperative vibrator connected to the platen, and

means whereby a movement of the platen will set said vibrator into operation.

6. A coremaker's bench or table having a fixed top section to receive the working materials and a vibratory section or platen at least partially surrounded by the fixed section and on which the core box is filled and rapped.

7. A vibrating table provided with a relatively movable platen, a normally inoperative vibrator adapted to vibrate said platen, a valve for controlling the operation of said vibrator and means for controlling said valve by the movement of said platen.

8. A vibrating table provided with a relatively movable platen, a normally inoperative vibrator adapted to vibrate said platen, a valve for controlling the operation of said vibrator, and adjustable means for controlling said valve by the movement of said platen.

9. A vibrating table, a platen slidably mounted in the top of said table, means for yieldingly supporting said platen, a normally inoperative vibrator adapted to vibrate said platen, a valve for controlling the operation of said vibrator, a lever operated by said platen to control said valve, and adjustable means for varying the position said platen must assume to operate said valve.

10. A vibrating table having a platen movably mounted in the top of the same, a vibrator secured to said platen to vibrate the same, a valve controlling said vibrator, said valve mounted upon said table, and means for opening and closing said valve by the movement of said platen.

11. A vibrating table having a frame mounted in the top thereof, a platen slidably mounted in said frame, yielding means for supporting said platen upon said frame, pneumatic means for vibrating said platen, and means controlled by the movement of said platen for starting and stopping said vibrator.

12. In a device of the class described, a fixed table, a platen slidably mounted in the top of said table, said platen having a lug formed upon its lower face at approximately the center of the platen, and a vibrator secured to said lug to vibrate the platen.

13. A vibrating table having a platen slidably mounted within the top of the same, said platen provided with yielding means for normally supporting the upper face of the same substantially flush with the upper face of said table, said platen constructed to be depressed within said table, and a vibrator operatively secured to said platen.

14. A vibrating table having a platen slidably mounted within the same, said platen compressible within said table, yielding means for normally urging said platen upwardly to its raised position, adjustable means for limiting the upward movement imparted to

said table by said yielding means, and a vibrator operatively secured to said platen.

15. In combination a coremaker's bench having a table provided with an opening in its top, a hollow frame mounted therein, a platen mounted to slide vertically within and supported by said frame, and a vibrator for vibrating said platen.

16. A coremaker's bench having a fixed top and a floating platen mounted in the top thereof, and means for vibrating the platen.

17. A coremaker's bench or the like having a fixed table section, and a floating platen substantially flush with said table section within the margins thereof.

18. A coremaker's bench or the like having a fixed table section, a spring supported platen at least partially surrounded by said fixed table section, and means for vibrating the platen independently of the fixed table section.

19. A coremaker's bench or the like having a fixed table section, a platen at least partially surrounded by said fixed table section and having its upper surface approximately flush with that of said fixed section, and means for vibrating the platen independently of the fixed table section comprising a rapping device directly connected to the platen at the underside thereof.

20. A coremaker's bench or the like having a fixed table section, a movable table section supported so as to be substantially flush with said fixed section, means for cushioning said movable section against downward movement, and a fluid actuated vibrating device directly connected to said movable section at the under surface thereof.

21. A coremaker's bench or the like having a fixed table section, a movably mounted section, means for cushioning the movable section, and a pneumatic vibrator attached

to said movable section at the under surface thereof, the longitudinal axis of said vibrator being disposed in the line of movement of said movable section.

22. A coremaker's bench or the like having a fixed table section for holding the working materials, a platen substantially flush with the upper surface of the fixed table section and at least partially surrounded by the latter, resilient means for yieldingly maintaining the movable section in the flush position, and means for setting the movable section in vibration comprising a pneumatic vibrator attached directly to the movable section and having a suitable controlling valve.

23. A coremaker's bench or the like having a movably mounted platen, and means for setting said platen in vibration by a movement thereof of predetermined amplitude.

24. A coremaker's bench or the like having a compressible platen, and means for setting the platen in vibration by depression thereof.

25. A coremaker's bench or the like having a floating platen, and means for setting the platen in vibration by depression thereof to a predetermined extent, comprising a fluid operated vibrator having a controlling element shiftable by depression of the platen.

26. In a device of the character described, a table, means for supporting a core-box on said table, a normally inoperative vibratory device for vibrating the core-box, and means whereby a movement of the box will set said vibratory means into operation.

In witness whereof, I have hereunto set my hand on the 22nd day of August, 1919.

GEORGE B. PICKOP.
